COMBINATION BEVERAGE DISPENSER AND COOLER

Edgar C. Harrison, Charles Town, W. Va., assignor to The Victor Products Corporation, Hagerstown, Md., a corporation of Maryland

Application February 18, 1955, Serial No. 34,570

Term of patent 3½ years

(Cl. D2—3)

Fig.1

Figure 1 is a perspective view looking to the rear and one end of the combination beverage dispenser and cooler showing my new design;

The broken away portions indicate indeterminate length.

I claim:

The ornamental design for a combination beverage dispenser and cooler, as shown and described.
